DOUGLAS TEMPLE BENNETT, OF WINCHMORE HILL, ENGLAND

PREPARATION OF PHOTOGRAPHIC SOUND RECORDS

Application filed January 13, 1931, Serial No. 508,511, and in Great Britain January 9, 1930.

This invention relates to the preparation of so-called photographic sound records, such as those of so-called "talking" films, and in particular to the means which are employed 5 for producing the varying light which is employed.

The invention has for an object to provide an improved method of and means for producing a varying light or glow emission corresponding with a varying electric current, such as the so-called "speech" current from a microphone.

According to the invention, a method of producing a varying light or glow emission 15 corresponding with a varying electric current consists in passing a varying electric current through an electrode, of which a part at least is comprised by a resistance element, of an electric glow discharge device, such as a 20 neon lamp.

The flow of varying electric current through a resistance electrode of a glow discharge device may serve to modify the potential difference between it and another electrode 25 of the device, and hence the glow emitted by the latter. Alternatively, the flow of varying electric current through a single, resistance, electrode of a glow discharge device may serve to modify the potential difference 30 between parts thereof, and thus to modify the glow emitted.

In cases where the flow of varying current through a resistance electrode serves to modify the potential difference between it and a 35 second electrode, it is desirable that the resistance electrode should be connected at one end, or at a given point in the length thereof, through a source of electro-motive force, with said second electrode. In all cases, however, 40 it is desirable that a source of constant electromotive force should be connected in series or in parallel with the resistance electrode, so that when no varying current flows through the latter, there will be a fall in potential 45 along the resistance electrode which will be modified as soon as varying current flows therethrough.

The invention is illustrated by the accompanying drawings, which are circuit diagrams, of which:

Figure 1 shows a simple arrangement employing a two-electrode discharge device;

Figure 2 is a corresponding arrangement showing a discharge device having a single electrode;

Figure 3 is a diagram of the type of sound record obtained by the use of either of these circuit arrangements;

Figures 4 and 5 show alternative arrangements employing two electrodes in a single 60 discharge device, respectively, and

Figure 6 is the type of sound record to be obtained by the use of either of these arrangements.

Referring first to Figure 1 of the drawings, a glow discharge device 11 has two electrodes, one 12 in the form of a wire or strip of conductive material, and the other 13 of resistance material, such as a carbon filament or coiled "resistance" wire extending 70 alongside the first from end to end. One end 14 of the resistance electrode is connected through a source of constant electro-motive force 15, such as a "high tension" battery, with the equipotential electrode 12, 75 whilst to that pole 16 of this interelectrode source 15, which is connected with the end 14 of the resistance electrode 13, is connected in this particular case a (like) pole 17 of a second source or battery 18, the other pole 80 19 of which is connected through a source of varying electric current, such as the secondary winding 20 of an output transformer of an audio-frequency thermionic valve amplifier (not shown) with the other end 22 of the resistance electrode 13.

In cases where it is undesirable that the steady flow of current through the resistance electrode 13 should pass also through the source of speech current 20, (e. g. to avoid 90 saturation of an iron core), the source 18 of electro-motive force (hereinafter referred to as the "biassing" source) may be connected in parallel with the resistance electrode 13, whilst the source of varying electric current 20 is connected in shunt with, or across, this parallel circuit through the medium of one or more electro-static condensers. Such 95 arrangement is to all intents and purposes virtually the same electrically as that 100

shown in Figure 1, and is therefore not illustrated.

In either case, however, it will be observed, firstly, that the potential difference between the end 14 (hereinafter referred to as the "constant potential" end) of the resistance electrode 13 and the equipotential electrode 12 will remain always constant at a value equal to the potential of the interelectrode source 15, and, secondly, that when no varying current flows, the potential between the other end 22 of the resistance electrode 13 (hereinafter termed the "varying potential" end) and the equipotential electrode 12 will be less (more if the source 18 be reversed) than the potential of the interelectrode source 15 by an amount depending upon the steady current flowing through the resistance electrode 13 from the biassing source 18; the interelectrode potential increasing along the length thereof, i. e. from the maximum at the constant potential end 14 of the resistance electrode. The potential of the biassing source 18 should not be less than the maximum peak potential of the varying current from the source 20. Thus, when the varying current flows, corresponding potential variations will alternately assist and oppose the potential of the biassing source 18, so that the interelectrode potential difference at the varying potential end 22 of the resistance electrode 13 will alternately decrease and increase with the varying current. As a result, the interelectrode glow, which, when no varying current flows, extends, for example, half way along the interelectrode space, as indicated at *g*, from the constant potential end 14, will vary in length from said end between two extremes; at one, the shorter, of which the varying current peak potential assists the biassing source 18, and at the other, the longer, of which said peak potential opposes the biassing source; the variations in the length of the glow being exactly in accordance with the variations in the varying current, in amplitude and periodicity; and being produced by variations in the position of that point in the length of the electrodes at which the potential between said electrodes is at that critical value which is just sufficient to cause a glow emission.

In the case of Figure 2 of the drawings, a glow discharge device 23 has a single electrode only comprised by two limbs 24 and 25, each in the form of a resistance element. A source 26 of varying electric current is connected in series with a biassing source of constant electro-motive force 27 across the ends 28, 29 of the electrode 24, 25 and the potential thereof is so chosen that normally the glow will extend from the free ends 28, 29 of the limbs 24 and 25 to a point intermediately of their length, as, in this case also, indicated at *g*.

From the above it will be apparent that as 55 the varying electric current from the source

26 alternately assists and opposes the biassing source 27, so will the length of the glow between the two electrode limbs 24 and 25 increase and decrease in length from the free ends 28, 29 of said limbs.

With this arrangement of Figures 1 and 2 of the drawings, it is possible to obtain a sound record of the type shown in Figure 3, the glow being projected upon a moving strip of sensitized material in a known or convenient manner. So long as no varying current flows, a given constant width, say one half of the strip from side to side, may be affected or exposed, as shown at 30, Figure 3. Upon the flow of varying current, the boundary of the affected or exposed part of the strip will change from a straight line to a line, the distance of which from the edge of the strip will vary in accordance with the varying electric current, as shown at 31.

A linear or area record obtained in this manner is much more accurate (i. e. free from distortion) than those obtained by the use of oscillosograph devices, owing to the complete absence of moving parts and the consequent 90 inertia lag.

As shown in Figure 4, it is possible, by the use of a resistance electrode 32 having a constant potential point intermediately of its length, preferably midway between its ends, as shown at 33, instead of at one end, that the interelectrode glow of a two-electrode discharge device 34 may be caused to expand and contract at both ends lengthwise of the electrodes 32 and 35 from the given or normal length, indicated in this figure also by *g*, so that there may be obtained a record (see Figure 6) in the form of an affected or exposed band extending centrally lengthwise of a strip of sensitized material, both boundaries of which band, and thus the overall width, will be varied from the normal, shown at 36, in accordance with the varying current to be recorded, as shown at 37.

In such a case two biassing sources of electro-motive force, and two independent feeds from a source of varying current to the sections of the resistance electrode 32 at either side, respectively, of the constant potential point 33 of the latter may be employed, but, as shown in Figure 4, an interelectrode source 38 is connected between the equipotential electrode 35 and the constant potential point 33 of the resistance electrode 32; a biassing source 39 and a source of varying current 40 being connected in series between said constant potential point 33 and the free ends, respectively, of the resistance electrode 32.

In order to obtain a glow emission capable of expanding, as in the case of Figure 4, at both ends, a single electrode glow discharge device may be arranged, as shown in Figure 5 of the drawings, for example, to obtain a record such as shown in Figure 6. In this case a glow discharge device 41 is provided

with a single electrode having two pairs of limbs 42, 43 and 44, 45, respectively, the limbs of each pair being connected in series, whilst the free end of the limb 42 of the one pair is connected with the free end of the corresponding limb 44 of the other pair, of which the limb 45 is connected with the limb 43 of the first pair. The junction of the limbs 43 and 45 is connected through a biasing source 46 and a source of varying current 47 with the junction of the limbs 42 and 44 of the electrode. It will be observed that in this case the glow emitted will vary in length from the normal, indicated by g , in accordance with the varying electric current from the source 47, which will alternately assist and oppose the biasing source 46.

It is well-known that linear or area records of the kind illustrated in Figures 3 and 6 are much less subject to inaccuracies brought by developments and printing processes, to which photographic sound records must inevitably be subjected, than are "density" records in which the opacity or transparency 25 across the full width of a record strip varies in accordance with the recorded varying current.

It will be observed by those skilled in the art that by the use of a varying glow in an electric glow discharge device according to the present invention, it would be possible to obtain a combined linear or area and density record, i. e. a record in which the opacity or transparency of the affected or exposed band of a sensitized strip which varies with its width, which in turn varies in accordance with the recorded current. Such a combined type of record could be obtained by so choosing the potential of the biasing source of electro-motive force, and that of the interelectrode source, where employed, that wherever the glow emitted increases or decreases in length from the constant potential point, or end of the resistance electrode, so the intensity of the glow at that point or end will increase or decrease. Here it should be noted that in all cases, see Figure 2, there will be a constant potential difference between the free ends 28 and 29 of the single electrode and that in Figure 5 this constant potential will obtain between the junction of the limbs 42, 44 and of the limbs 43, 45.

In Figures 4 and 5, the arrangement is such that the glow expands and contracts from the centre of the tube, but it will be apparent that analogous arrangements could be used where the glow extends from each end of the tube towards the centre.

It will also be observed that where an equipotential electrode is employed, this may be such (e. g. of a U-shaped cross section) as almost completely to surround the resistance electrode in order to obtain better control or intensity of the glow.

In some cases it may be possible, with a

view to rendering the variations in glow in length or area more directly proportional to the varying electric current which produces them, to employ other than straight electrodes and/or to mount the electrodes at an angle to one another. Again, it may in some cases be desirable that the resistance of the resistance electrode should not be constant per unit length.

Finally, it will be observed that where one or two electrodes are employed, either or both may take various forms; for example, a resistance electrode could be of substantially spiral formation and used in conjunction with an equipotential electrode in the form of a circular plate mounted alongside it.

Various gases and combinations of gases may be employed in the glow discharge device, and it has been found that, although the varying glow emission according to the invention is intended particularly for use in the production of photographic sound records, it could also be used *inter alia* in connection with a suitable viewing mechanism as an oscilloscope for communication purposes, or even in electric signs, in which the electrode or electrodes could be in the form of symbols. It is possible also that in some cases it may be desirable to employ a glow discharge device having two resistance electrodes in place of one having one resistance and one equipotential electrode. Moreover, inasmuch as rays emitted by an electric glow discharge device are not necessarily within the range of a visible spectrum, the varying glow according to the present invention need not necessarily be a visible, or wholly visible one.

What I claim is:—

1. A method of producing a varying light or glow emission corresponding with a varying electric current, which consists in passing the varying electric current through an electrode, of which a part at least is comprised by a resistance element, of an electric glow discharge device, such as a neon lamp.

2. A method of producing a varying light or glow emission corresponding with a varying electric current, as claimed in claim 1, wherein the flow of varying electric current through a single, "resistance", electrode of the discharge device serves to modify the potential difference between parts thereof, and thus to modify the glow emitted by the device.

3. A method of producing a varying light or glow emission corresponding with a varying electric current, as claimed in claim 1, wherein a "resistance" electrode is connected at one end or at a given point in the length thereof through a source of electro-motive force with another electrode of the device.

4. A method of producing a varying light or glow emission corresponding with a varying electric current, as claimed in claim 1,

wherein a resistance element is connected at a point intermediately of its length with one pole of a source of varying electric current, the other pole of which is connected with the 5 ends of said electrode.

In testimony whereof I have hereunto signed my name.

DOUGLAS TEMPLE BENNETT.
